J. DINERS,
MEANS FOR PROTECTING SHIPS FROM TORPEDOES,
APPLICATION FILED AUG. 22, 1918.

1,305,700.

Patented June 3, 1919.

UNITED STATES PATENT OFFICE.

JULIUS DINERS, OF NEW YORK, N. Y.

MEANS FOR PROTECTING SHIPS FROM TORPEDOES.

1,305,700.

Specification of Letters Patent. Patented June 3, 1919.

Application filed August 22, 1918. Serial No. 250,953.

To all whom it may concern:

Be it known that I, JULIUS DINERS, a citizen of the United States of America, residing at New York, in the county of New 5 York and State of New York, have invented certain new and useful Improvements in Means for Protecting Ships from Torpedoes, of which the following is a specification.

10 The present invention relates to the protection of voyaging ships from torpedoes projected from submarines.

The principal object of my invention is to provide simple and effective guards at 15 the sides of the ship which will be capable of deflecting the course of a torpedo and prevent the torpedo from reaching the ship.

Another object of my invention is to so construct the guards that they will be buoy- 20 ant bodies and therefore not add to the load of the ship.

A further object of my invention is to so arrange the guards so that they will not interfere with the speed of the ship, with her 25 ability to maneuver nor with the launching of life boats or rafts.

A still further object of my invention is to attach the guards to the ship so that they can be easily and readily detached whenever 30 desired and on the detonation of the torpedo will be liable to become detached from the ship.

And a still further object of my invention is to provide guards which at the same 35 time will serve as stabilizers for the ship in a heavy sea.

With these and other objects in view which will hereinafter appear more clearly from the detailed description of my invention, 40 my new guard, of which I employ one on each side of the ship, consists of a buoyant body or a buoyantly supported body which can be easily and readily attached to the ship and which is so curved laterally 45 and downwardly that, at any point of the surface of the guard, the latter will be substantially tangent to the warhead of the torpedo when the latter reaches the guard so that the torpedo will be caused to ride up 50 the curved surface of the guard and will be prevented from striking the guard with its firing pin. These guards are adapted to be submerged in the water, a distance sufficient to cover the entire depth in which a 55 torpedo may operate. At the same time the

guards extending a considerable distance away from the sides of the ship will, in case of the detonation of the torpedo caused by friction while it is checked in motion, serve to intervene between the ship and the torpedo, so that only they will be destroyed or torn off the ship while the ship will remain intact and be allowed to proceed.

My invention will be more fully understood by reference to the accompanying drawing in which similar reference characters denote corresponding parts and in which Figure 1 is a front elevation of a ship and of my device attached to it; Fig. 2 is a side elevation thereof on a reduced scale; Fig. 3 is a cross section of a vessel equipped with my device somewhat modified in construction; Fig. 4 shows the device lowered to free the ship and Fig. 5 shows a more or less diagrammatic view of a further modification of the device.

Referring specifically to the drawing 1 denotes a vessel or ship of the usual construction, preferably of a standardized shape and size. The new device comprises principally 80 two wings 2, 3 extending one along each side of the vessel. These wings are curved surfaces which project laterally and downwardly and adapted to be submerged in the water, a depth calculated to cover the maximum depth in which a torpedo may operate. The curvature of each wing surface is calculated to be such that when the wings are in normal position the wing at any point will be substantially tangent to the warhead 85 of the torpedo when the latter reaches the guard. In Fig. 1 the warhead 4 of the torpedo 5 is shown to be tangent with the surface of the guard. By reason of such construction, the torpedo will be prevented 90 from striking with its firing pin 6. After striking with its head the surface of the wing, the torpedo will continue to propel itself; but instead of piercing the wing will ride up the same and thereby be deflected in its course given it by its gyroscopic mechanism.

The wings 2 and 3 may be made in form of grates as shown in Figs. 1 and 2 or as otherwise suitably perforated surfaces or may be 105 formed as solid plates 2', 3' as shown in Fig. 3.

The wings may be suitably fixed to a frame work 7 which may snugly engage around the sides and the bottom of the ship 110

(Figs. 1, 2 and 3) and which by flexible or suitable means 8 may be detachably fixed to the ship.

By providing air tanks 9 suitably supported on or suspended from the frame 7 or the rear surfaces of the wings (Figs. 1 and 2) the guards will be rendered buoyant so that they will not add to the load of the ship. Instead of providing special tanks, the space 10 between each wing and the corresponding side of the frame 7 may be closed all around and serve as an air container, as shown in Figs. 3 and 4.

When it is desired to release the frame 15 and wings or guards from the ship, the air tanks or air containers may be filled with water through pipes 11 so that the device, after its detachment from the ship, will be lowered in the water freeing the ship. Particularly when standardized ships are used such construction may be useful. The ship approaching a harbor may, as above described, be freed from the device while another ship leaving the harbor may enter the frame 7 which, after the discharge of the water, will rise and can then be attached to the new ship.

The wings 2 and 3 will also have the effect of greatly reducing the rolling motion of a 30 vessel in a heavy sea and thus serve as stabilizers.

The frame 7, however, may be entirely dispensed with and the wings 2 and 3 can be suspended directly from the ship in such a 35 way that when a wing is struck by a torpedo it will of itself become detached from the ship. Such construction is more or less diagrammatically shown in Fig. 5. Here the wings 12 and 13 are hooked at 14 or otherwise so suspended from the sides of the ship that when one of them is struck by a torpedo it will, upon the detonation of the torpedo, be thrown off the hook or the like. Each of the wings may be formed at its free end with an air tank 15 so as to be buoyant.

While the primary object of the wings is to serve as deflectors, it is clear, that even if they fail to deflect the torpedo by reason of the rocking movement of the ship or for 50 any other reason and will cause the torpedo to explode, the explosion will not affect the ship since the explosion will take place a considerable distance away from the ship.

Copies of this patent may be obtained for five cents each, by addressing the "Commissioner of Patents, Washington, D. C."

As the wings are not rigidly but detachably fixed to the ship, all that may happen is that the wings when struck by the torpedo will be thrown or torn off the ship without materially affecting the latter.

The wings being made buoyant there will be no additional load on the ship to carry the 60 wings. The plates of which the wings are made may be comparatively thin so as to but little interfere with the maneuvering of the ship.

While I have shown and described in detail the construction of my new device, I of course do not wish to restrict myself to the same, for anyone skilled in the art and familiar with the principles of the operation 65 of torpedoes may readily modify the construction without departing from the principle of my invention.

What I claim and desire to secure by Letters Patent is:

1. In combination with a ship, a device for 75 protecting the same from torpedoes, consisting of a framework conforming in shape with the sides or bottom of the ship and adapted to removably engage the latter, wing shaped deflector members projecting from 80 said frame and curved so as to be substantially tangent to the warhead of an approaching torpedo, and air tanks for rendering the device buoyant, said air tanks being capable of being filled with water to allow 85 the lowering or submerging of the device.

2. In combination with a ship, a buoyant 90 device for protecting the same from torpedoes, consisting of a frame adapted to removably engage around the ship, wing shaped members projecting from said frame laterally and downwardly and serving as deflectors for approaching torpedoes, the space 95 formed between said wings and said frame being closed all around to form air tanks and a pipe leading into said air tanks and enabling the filling of the latter with water to lower or submerge said device after its detachment from the ship.

In testimony whereof I affix my signature 100 in presence of two witnesses.

JULIUS DINERS.
